[57] ABSTRACT

Copy sorting and distributing apparatus for automatically depositing a preselected number of copies in particular storage spaces. A switch selects a particular program which is arranged to indicate particular numbers of copies or articles to be deposited in particular bins. The program units together with switch mechanism represent copy counting mechanisms which automatically reset themselves and set up the apparatus for depositing copies in a succeeding space. Program units may be changed automatically.

ARTICLE DISTRIBUTOR

The present invention is directed to apparatus for distributing preselected numbers of articles in particular article-receiving spaces, and is particularly concerned with improvements in controls for such apparatus.

The major purposes of the present invention are to arrange control circuitry for article distributing apparatus in a manner which allows use of any selected one of program controls, each of which is set to control the distribution of articles in preselected spaces in preselected numbers; to arrange control circuitry for apparatus of this class in a manner enabling convenient use with different kinds of program controls; to arrange apparatus of this class in a manner which allows an automatic, manual, or external control signal to return the apparatus to an initial or "home" condition; to arrange apparatus of this class with a means for counting copies of articles deposited in a particular space while completing a control signal to reset the copy counting facilities and automatically recondition the apparatus for reception of articles in another space when the required number of articles have been deposited in a particular space; to arrange a copy counting means to cause simultaneous closure of one space and opening of the next when the required count for one space is complete; to arrange control circuitry in apparatus of this type to enable skipping of a particular article space when no articles are desired in that space to thereby increase speed of operation; and to arrange control circuitry for program control units in apparatus of this class in a manner allowing selection of the next program unit in sequence after a particular program unit has started followed by automatic or manual connection of the next unit in circuit after the particular unit is completed.

These and other purposes will appear from time to time in the course of the ensuing specification and claims when taken with the accompanying drawings, in which:

FIG. 1 is a side view of a typical copy distributing apparatus used in the invention;

FIGS. 2, 3 and 4 represent a circuit diagram incorporating the principles of the present invention and should be considered together as one entity;

FIG. 5 is a diagram of a portion of the circuit illustrated in FIGS. 3 and 4 and illustrating particular circuit power conditions for resetting a copy counting switch and for activating a bin selector switch;

FIG. 6 is a diagram of a portion of the circuit illustrated in FIGS. 3 and 4 while illustrating power conditions for resetting a copy counting switch utilized in the invention;

FIG. 7 is a diagrammatic view of portions of the circuit illustrated in FIGS. 3 and 4 and illustrating power conditions in the circuits for returning a bin selector switch to a "home" or initial position; and

FIG. 8 is a circuit diagram of an automatic and manual program selector unit which may be used with the circuit of FIGS. 2-7.

Like elements are designated by like characters throughout the specification and drawings.

With specific reference now to the drawings, and in the first instance to FIG. 1, the numeral 11 designates the frame of a document sorting and distributing ap-

paratus of the type disclosed in Anderson et al. U.S. Pat. No. 3,371,926. As disclosed in said patent, the frame supports a deck 12 for receiving documents from a duplicating machine and for feeding documents along the machine in the direction of the arrow represented in FIG. 1 for selective distribution in a plurality of document-receiving trays 13 which are in spaced relation longitudinally of the machine and along the path of movement of the documents to be distributed. Rollers 14 may support the documents for feeding the same along the path for distribution to the trays 13. The entrance to each tray 13 is selectively opened and closed by gate mechanism 15 as fully disclosed in said patent. An operating solenoid 16 is connected to each gate so that when a particular solenoid 16 is energized, the gate mechanism interconnected therewith is actuated so as to open the entrance to a tray associated with that energized solenoid and direct a document into the tray. The arrangement is such that as long as a gate is open and as long as documents are fed in spaced relation along the path, copies will continue to be distributed through the gate opening and into the particular tray associated with that opening. Thus, the number of documents received in a particular tray is dependent upon the time that the gate to a tray is open. When the gates are closed, the documents simply pass the entrances to the trays associated with the closed openings and pass further along the machine until they reach a tray entrance which is open.

As further disclosed in said patent, microswitches 17 are associated with each gate mechanism with actuating mechanism for the microswitch which is closed when the leading edge of a document actuates feeler arms for the microswitch and the microswitch is opened when the trailing edge of the document passes the feeler arms.

In accordance with the present invention, a program controlled electrical circuit is employed for energizing a selected gate solenoid 16 and for holding a gate for a particular tray open for a preselected time corresponding to reception of a preselected number of copies of documents in a particular tray. This circuit is illustrated in FIGS. 2, 3 and 4. In FIG. 2, for example, four actuating solenoids 16-1-16-4, respectively, are designated for controlling the gate openings corresponding to four different document-receiving trays or bins. The last bin does not need a gate operating solenoid. Its gate may be locked open. It should be understood that a larger number of document-receiving trays, gate operating solenoids and associated sensing microswitches may be employed or a lesser number may be employed. The sensing microswitches are designated by the numerals 17-1, 17-2, 17-3, 17-4 and 17-5, respectively. The several gate operating solenoids 16-1, etc., for the various gate openings for the bins or trays are in parallel with one another and are adapted to be energized from a source 18 which may be D.C. The sensing switches 17-1-17-5, inclusive, are also adapted to be energized from the DC source 18.

The circuit from the DC source 18 to each of the gate operating solenoids 16-1-16-4 and the circuit to the sensing switches 17-1-17-5 include switches which are normally open and which are adapted to be closed by control relays for each bin or tray which are designated 19-1 through 19-5, inclusive. For example,

the DC energizing circuit for each bin solenoid includes a normally open switch 19-1a through 19-5a and the circuit to each sensing switch includes a normally open switch 19-1b through 19-5b under control of the relays 19-1 through 19-5, respectively. When a particular bin relay, as for example relay 19-1, is energized, its associated contacts 19-1a and 19-1b close the DC circuits to the associated bin solenoid 16-1 and to the bin document sensing switch 17-1. The circuit is arranged so that only one of the relays 19 is energized at a time whereby one gate mechanism is open at a time and the circuit to the sensing switch 17 for that particular gate is closed at that time.

The gate operating solenoids 16, sensing switches 17, relay contacts 19-1a and 19-1b and their DC source thus present activating circuits for each bin under control of the relays 19.

Each of the bin solenoid operating circuits may include manually operated switches 20-1, 20-2, 20-3 and 20-4 which are in parallel with the switches 19-1a through 19-5a, respectively, so that the operator may energize a particular bin solenoid and hold it open as long as the manually actuated switches are closed. Pilot lights 21 may be in the circuit for each of the gate mechanism actuating solenoids so as to indicate when a particular gate is open. Capacitors 22 may be associated with each of the switch contacts 19-1a through 19-5a, inclusive, for arc suppression.

In order to select a bin or tray for reception of copies, and to automatically place a preselected number of copies in each bin, bin selector switches 23, 24, 25 and 26 are utilized to energize one activating circuit for a bin at one time, set up a counting circuit for each bin, and circuits to automatically energize the next bin activating circuit when the count for a particular bin is satisfied. A copy counting switch 27 is also used with a circuit to count the number of copies having entered each bin. The switches 23-26 may be different contact banks of a single switch. Each of the switches 23-27 is in the form of a rotary stepping switch with a movable contact arm as designated at 23a-27a, inclusive, and with a plurality of contacts adapted for sequential engagement with the movable contact arm during rotation of the movable contact arm.

Coil 29 is adapted to be energized from a line 29a leading from the sensing switches 17 and from a holding circuit which will be described. Coil 28 is energized from circuitry which will be described. The switches 23-26 may be ganged switches under control of a single electromechanical operating means. Switches 23-26, for example, may be controlled by an operating coil 28, while switch 27 may be operated by an operating coil 29 (FIG. 4). These switches are rotary stepping switches and are of the type wherein, when the coils 28 and 29 are energized, an operating pawl is "cocked" and then when the circuit to the coil is broken, the pawl moves the movable contact arms to the next contact. Switches of this type are known to the electrical arts.

Switch 23 is adapted to establish an energizing circuit to one of the gate control relays 19 for a selected bin, while switch banks 24, 25 and 26 are adapted to set up circuits through programs for predetermined numbers of copies to be deposited in each bin. Each of the switches 24, 25 and 26 is shown arranged with a different program unit, each of which represents a dif-

ferent number of copies for each bin. The program selector units shown in FIG. 2 are intended to be representative of matrix boards with a series of wires running at right angles to one another, as shown, or ganged rotary or thumbwheel selector switches with one switch for each bin. A first set of generally parallel wires 30 through 40 may lead to the stationary contacts of the selector switch 27 and represent numbers of copies to be distributed in a particular bin. The line 31 represents one copy, the line 32 represents two copies, and so on, down to ten copies for line 40. Line 30 represents zero copies for a particular bin and is directly connected to a source of current as indicated.

A second set of parallel wires 41 through 45 is shown in program No. 1 and extending at right angles to the copy number representing lines 30-40. These lines lead to the stationary contacts of the selector switch 24 (or 25 or 26). Each line represents a different bin or tray to receive copies. The crossing areas of the lines 30-40 and 41-45 may be connected by metal pins or contacts P at selected points, as shown, so that bin No. 1 is to receive one copy, bin No. 2 is to receive two copies, bin No. 3 receives no copies, bin No. 4 receives 10 copies, and bin No. 5 receives three copies. The pins P thus establish an electrical circuit line between a particular stationary contact in switch 27 representing a particular number of copies and a particular stationary contact in switch 24 representing a particular bin. Programs No. 2 and No. 3 have similar parallel circuit lines at right angles to the copy number representing lines as in the case of program No. 1, and may have metal pins set for different numbers of copies set for each bin as shown. The bin representing lines of program No. 2 lead to the stationary contacts of selector switch 25 in sequential order as do the bin representing circuit lines of program No. 3 to the stationary contacts of selector switch 26. These program selector units are utilized to establish a circuit to reset the copy counting stepping switch 27 to the zero or "home" position when a particular bin has received the required number of copies. The circuit is broken as long as a particular bin has not as yet received its required number of copies.

It should be understood that the representation of five bins and 10 copies is only illustrative. Any number of bins and any number of copies may be programmed for each bin in the manner stated. Also, in lieu of a matrix contact board as described, other forms of program selector units may be utilized with the stepping switches in the general fashion described.

The movable contacts 24a, 25a, 26a of the selector switches are connected to separate contacts in a selector switch 50 which is connected to a circuit line 51. Switch 50 enables selective connection of a particular program to the circuit line 51. Circuit line 51 leads to an operating circuit for the coil 29 which activates the movable arm 27a of switch 27 in a manner to be described.

Power is supplied to the movable contact arms 23a and 27a of the bin selector switch 23 and copy counting switch 27 through a main on-off switch 52 which is adapted to close circuit lines to the movable contact arms 23a and 27a and power lines 53 and 54 which are connected to a main power source which is shown as a DC source. A diode 55 may be in the power line 54 to allow current flow from the DC source 56 while preventing flow in the opposite direction.

The operating coil 28 for the bin selector switches 23, 24, 25 and 26 has a number of switch contacts associated therewith. Contacts 28a and 28b are normally closed contacts which open when coil 28 is energized. The rotary element of the stepping switches rotates a cam 28c in synchronism with movement of the contact arms 23a-26a. Cam 28c is adapted to close switch contacts 28d and 28e in one position of the cam corresponding to the "home" or bin No. 1 position of the stepping switch. When cam 28c rotates away from this position, the contacts 28d and 28e open while a contact 28f is closed (as shown in dotted lines in FIG. 4).

The operating coil 29 for the copy counting switch 27 has a number of contacts associated therewith in a fashion similar to the coil 28. For example, switch contacts 29a are normally closed but are opened whenever coil 29 is energized. The rotary element of the stepping switch operated by coil 29 rotates a cam 29c in synchronism with the rotation of the movable contact arm 27a. When the movable contact arm 27a is in the "home" position, which is the position illustrated in FIG. 2, or a position immediately preceding the contact for copy No. 1, cam 29c holds switch contacts 29d and 29e closed. When cam 29c moves away from the "home" position, it allows movable contacts operated thereby to open the contacts 29d and 29e and close contacts 29f and 29g (as shown in dotted lines in FIG. 4).

The circuit also includes relays 56, 57, 58 and 59, each having a number of contacts operated thereby. Relay 56 establishes a holding circuit for energization of coil 29 for returning switch 27 to the "home" position each time the count is satisfied for a particular bin. Relay 56, for example, when energized, opens normally closed contacts 56a, 56b, 56c and 56d and closes contacts 56e, 56f, 56g and 56h (as shown in dotted lines). All of these contacts may be armature type in which an armature normally closes the contacts 56a, 56b, 56c and 56d when relay 56 is deenergized while opening these contacts and closing contacts 56e, 56f, 56g and 56h when the relay is energized.

Contact 56b is in the power line 54 leading to the copy counting switch. This power line is thus opened whenever relay 56 is energized for purposes of returning the copy counting switch to the "home" position. This prevents extraneous signals during this time period.

Relay 57 also has armature type switch contacts operated thereby. Relay 57, for example, has normally closed contacts 57a and 57b which are opened when relay 57 is energized, and contacts 57c and 57d which are closed (as shown in dotted lines in FIG. 3) when relay 57 is energized. The normally closed contacts 57a are in the main power line 53 leading through switch 23 to the bin control relays 19. Power is thus cut off to the bin control relays when relay 57 is energized to eliminate unnecessary relay action.

Relay 57 and another relay 58 are used to control circuits for selectively energizing coil 28 of the bin selecting stepping switches 23-26, inclusive, for returning the movable contact arms thereof to the "home" position. Relay 58 includes a number of armature type switch contacts operable by the relay. These contacts are normally closed contacts 58a, 58b, 58c and 58d. These contacts are opened when relay 58 is energized and the movable contacts then close contacts 58e, 58f,

58g and 58h (as shown in dotted lines). Diodes 58i and 58j are in line from the armatures for contacts 58b and 58c and to a line to the armature for the contact 58a.

Another relay 59 may be termed a bin shift relay and controls pulses of current to coil 28 for purposes of stepping the switches 23-26 from one bin position to the next. Relay 59 includes armature type switch contacts operated by the relay. It includes normally closed contacts 59a and 59b which are opened when relay 59 is energized, and normally open contacts 59c and 59d which are closed when relay 59 is energized (as shown in dotted lines).

The circuit includes a circuit line leading to relay 58 through an on-off switch 60 to a contact in selector switch 23, which is the next contact in sequential order in the switch after the last bin relay connected contact. This circuit line is to establish an automatic return of the bin selecting switches to the "home" position after the required number of copies have been distributed in all bins in a manner which will be described. The circuit also includes a pair of leads 62 and 63 which are adapted to bypass the switch contacts 58a and 58e under control of a manually operated switch 64 or an external switch input, as indicated at 65 and 66, for purposes of selective energization of relay 58 independently of use of circuit line 61 for automatic return of the bin selector switches and copy counting switch to the "home" position.

At the start of operation, and with the bin selector contact arms 23a and 24a in the bin No. 1 position, power is supplied through line 53 to the bin relay 19-1 to close contacts 19-1a and energize bin solenoid 16-1 to open the gate for bin No. 1 and close contacts 19-1b for energizing the detector switch 17-1. This sets up the copy counting cycle. The power present in the circuit at this time is represented by the heavy lines in FIGS. 2, 3 and 4. Pulses of momentary power in line 29a are represented in heavy dash lines in these figures. As the leading edge of a copy passes into the bin, it closes switch contact 17-1 which energizes coil 29 through line 29a and cocks the stepping switch. When the trailing edge of the copy passes switch 17-1, switch 17-1 opens and breaks the power to coil 29. Prior to the time that the stepping switch advances one contact, the movable contact arm 27a is in the "home" position which is illustrated in FIG. 2, and the circuit through the program selector unit is thus open. After coil 29 operates the arm 27a through one step in response to opening of switch 17-1, this corresponds to one copy and the contact arm 27 moves to the first contact corresponding to one copy. If it is assumed that a contact point P is present at line 31 for designating bin No. 1 for one copy only, the circuit is then completed from switch 27 to switch 24 and power is then supplied from line 54 to movable contact 27a and through the point P at the intersection of lines 31-41, through movable contact arm 24a, through line 51 and through the now closed contact 29g to relay 56 (cam 29c has rotated with the switch to open contact 29f and close contact 29g). Upon energization of relay 56, power through the program selector unit is broken by opening contacts 56b while the energization of relay 56 is maintained by the closing of holding contacts 56f. The momentary "count complete" signal in line 51 is represented in heavy dash lines in FIG. 5 while heavy full lines indicate

the power condition in the circuit after holding relay 56 is energized. Contact 56h also closes, which closes a circuit line 67 through the interrupter switch 29a to coil 29 and the energization of coil 29 is maintained to step contact arm 27a around to the initial or "home" position. The circuit to the coil 29 is broken when "-home" position is reached because of the opening of contacts 29g and 29f by cam 29c which breaks the power to relay 56. The counting cycle for bin No. 1 is thus complete.

If bin No. 1 was set for more than one copy, the circuit through the program selector unit would not be completed for energization of relay 56 until a number of stepping pulses to coil 29, corresponding to the passage of a desired number of copies to the bin, had advanced the movable contact arm stepwise to the required or selected contact position connected to line 41. At that time the circuit through the program selector unit would be momentarily completed to energize relay 56 and cause energization of coil 29 and return of contact arm 27a to the "home" position as previously described.

After the count for the first bin is satisfied, the circuit automatically disables the power to bin control relay 19-1 to thereby deenergize gate solenoid 16-1 while moving the movable contact arms 23a-26a to the bin No. 2 position. At the bin No. 2 position, the contact arms energize the bin control relay 19-2 and the bin gate operating solenoid 16-2 in the manner described for solenoid 16-1 and set up the circuit lines in the program selector unit for bin No. 2 operation.

The circuit for advancing the switches 23-26 to the next bin control relay will now be described. At the time of initial operation, normally closed contacts 56b establish power through a circuit line 68 through the movable contact for contact 59a to relay coil 59. This energizes relay 59. When relay 59 is energized, it closes contacts 59c and 59d which establishes a holding circuit for the relay through contact 59c. This holding circuit establishes power to the relay through the interrupter switch contacts 28a and line 68a. This circuit condition is represented by the heavy full lines of FIGS. 3 and 4. When the signal from the program selector unit indicates that the count for a particular bin is satisfied, relay 56 is energized as previously described and this closes contact 56g which in turn supplies current through line 68b, contacts 59d, 58d, and through a circuit line 68c to the coil 28. The condition of power in the circuit to relay 59 and coil 28 at the time of initial energization of coil 28 is shown in heavy full lines in FIG. 5. Energization of the coil cocks the switch for stepping the switch through one position, and this energization opens normally closed contacts 28a which breaks the holding power circuit to relay 59, which in turn discontinues the power to coil 28. The switch is then advanced one step which moves the movable contact arms 23a, 24a, 25a and 26a to the next contact position which is the bin No. 2 position. When the coil 28 advances the rotary arms away from the number 1 or "home" position, cam 28c opens contact 28e and closes contact 28f. Contact 58d prevents extraneous signals to coil 28.

In the event that the program for the next bin in the series is set up for no copies in the bin, a signal from the program selector unit is immediately established when

the movable contact arm 24a moves to this bin position. This is represented in FIG. 2 by point P for bin No. 3. The "zero" copy line 30 is connected to a DC source. At this time, if contact 29e is closed because the copy counting switch is at the "home" position, a signal is passed from the program selector unit directly through the contact 29e and through a circuit line 70 and through interrupter switch 28b to relay 28. If the copy counting switch 27 has not returned to the "-home" position at the time of the zero copy signal from the program selector unit, power is then supplied to the coil 28 through a line 71 (connected to line 51) and through contact 56e (relay 56 is energized until switch 27 returns to the "home" position) and then to the power line 70. Energization of coil 28 in either fashion causes the switch to step to the next bin position.

The stepping of the copy counting switch 27 followed by "homing" of the switch and one step of the bin selecting switches 23, 24, 25 and 26 and/or skipping of bins when no copies are required, continues until the movable contact arms 23a-26a have moved through all of the bin positions and satisfied the count for each bin. Then bin selector switches 23-26 may be returned to the "home" position in one of several ways under control of reset or "homing" relay 58. Relay 58 is operative to reset both the copy counting switch 27 and bin selecting switches 23-26 to "home" position when energized. This may be effected by control of an external signal, a manual closure of the lines 62 and 63 which energizes relay 58, or automatically through line 61.

FIG. 6 is a diagrammatic illustration of circuit conditions for resetting the counting switch through energization of coil 29, and FIG. 7 is a diagrammatic illustration of circuit conditions for energizing coil 28 to reset or "home" the bin selecting switches. In FIGS. 6 and 7 the heavy dash lines represent momentary power for energizing relay 58 to in turn energize the holding relays 56 and 57 for the switch operating coils 29 and 28, respectively. Power for the holding relays 56 and 57 is established through the cam operating switches and switch contacts 28f and 29f associated with the coils 28 and 29 so that when the switches and the cams are at the "home" position relay 58 is ineffective to activate the coils. If one switch is at the "home" position while the other is not, relay 58 will be effective to energize the circuit to the coil to insure return of the switch associated with that coil to the "home" position. In FIGS. 6 and 7 the power path to the coils is represented in heavy full lines.

Relay 58 is energized in one of several ways. It may be energized through closure of the manual switch 64 or by closure of a switch across lines 65 and 66 and actuated by an external signal. In either of these two events, power to the relay is established through cam operated switch contact 29f and the armature for contact 58b (FIG. 6). An independent power supply for relay 58 is established through cam operated switch contact 28f, the armature for contact 57b and through the armature for contact 58c. Thus, relay 58 may be energized by the manual switch or the external signal when one or the other of the cams 28c and 29c is not at the "home" position or when both are away from the "-home" position. When relay 58 is energized, it closes contacts 58e, 58f and 58g. Contact 58e establishes

holding power for relay 58. A momentary source of power is then supplied to holding relay 56 for coil 29 through contact 58f. Relay 56 then locks itself in by virtue of closure of contact 56f and power is supplied to coil 29 through contact 56h as shown in FIG. 6. Power to holding relay 57 is supplied through contact 58g when relay 58 is energized. Relay 57 then locks itself in through contact 57d at the same time contact 57a is opened which discontinues the power to the bin control relays. Once relay 57 is energized, power is supplied through line 72 to the coil 28 until the coil returns the rotary switch arms to the "home" position. When coil 29 has returned its switch arms and cam to the "home" position, power supply to the holding relay 56 is broken by opening of switch contacts 29f. When coil 28 has returned its movable contact arms and cam to the "home" position, power supply to its holding relay 57 is broken through opening of switch contact 28f. When both cams 28c and 29c return to the "home" position, the power to relay 58 is broken because of opening of the contacts 28f and 29f.

For automatic return of the bin selector switches to the "home" or bin No. 1 position, switch 60 is closed. After the count of the last bin has been satisfied, coil 28 will have stepped the movable contact arms 23a-26a to the contact next beyond the last bin position. Current from line 53 then passes through the selector switch 23 and through line 61 to energize relay 58.

When relay 58 is energized, it causes energization of the holding relays 56 and/or 57 (depending upon whether one or both of the switches need returning to "home" position), and the circuit then operates as described for the manual or external signal "homing" operation.

When the stepping switches have been returned to the "home" position so that contacts 28d and 29d are closed, a circuit is established between these contacts and the power supply. This circuit may be utilized to operate a pilot light indicating that the apparatus is ready for another program. This circuit may also be utilized to automatically operate the program selector switch or external equipment.

The program selector switch 50 may be automatically advanced to the next program through use of electrically operated rotary stepping switches of the same type described for switches 23-27. The automatic "homing" signal line 61 may be utilized to actuate the operating coil for such a switch so that, when one program is completed, the next program designated is automatically switched into the line and a new programmed distribution of copies is automatically brought about. Alternatively, a signal for this purpose may be picked up from contact 28d. For each new program, the sequential opening of bins through operation of the control relays and deposit of a preselected number of copies in each bin is the same as has been previously described.

The control circuitry as disclosed herein enables a rapid change from one order of distribution to another. The manual "homing" switch 64 allows an operator of the apparatus to immediately reset the apparatus to a zero or "home" position in the event an erroneous program has been selected, or if the operator for some reason or another wishes to stop a particular program after it has once begun. The use of the signal from the

copy counting switches and programs to cause shifting of the bin selector switches enables a very rapid closure of an open bin and opening of the next succeeding bin. The use of the direct signal from the programmer when zero copies are desired enables an almost instantaneous energization of the bin stepping relay coil 28 from one position to the next. This direct signal from the program unit is supplied just as soon as movable contact arm 24a is in circuit through one of the lines 41-45 with the DC source. The circuit is arranged so that the bin shifting circuitry to the bin control relays is broken (through opening of contact 58d) whenever manual, external "homing" or automatic "homing" is in operation. This prevents erroneous operation of the bins during the "homing" cycle.

The program circuit may be switched off by opening switch 52 when desired so that an operator can use manual switches 20-1 to 20-4 to hold particular bins open for as long a time as desired.

FIG. 8 discloses an automatic program selector unit which allows the operator to immediately select the next program for use in automatic sequence after a particular program is started. In FIG. 8 a multicontact program selector switch 150 is utilized in place of the program selector switch 50 in FIG. 2. The selector switch has a movable arm 150a selectively engageable with a first bank of contacts including contact 151 and 152 with leads to the switches 24 and 25. Switch 150 has a second movable arm 150b selectively engageable with an additional bank of contacts 153 and 154 which lead to the operating coils 155 and 156 for latching relays. Coil 155, for example, is adapted, when energized, to move a movable armature 155a into closing relation with a contact 157 which leads to switch 24. Coil 156, when energized, is adapted to move the movable armature 155a against a contact 158. Only a pulse is necessary to cause the armature to move from one contact to the other and once so moved the armature stays with that contact until a coil is again energized. Contact 158 has a lead to the switch 25.

It should be understood that, when more than two program units are utilized, switch 150 will have additional contacts for the additional programs, i.e., one contact for each program. The movable arm 150a of switch 150 is then selectively movable into engagement with a selected one of the contacts when preselection is not desired so as to complete the circuit to the particular program selected. Switch 150 also has an additional bank of contacts for arm 150b and corresponding to the number of program units. Additional coils similar to coils 155 and 156 and their associated switches are utilized for the additional programs to enable a combination of coils and preselection of any particular program.

A preselector multicontact switch 160 has a first position wherein one movable contact 160a completes the circuit between the movable contact 150a and line 51. When the switch is in this position, the switch arm 150b and coils 155 and 156 are not used. The operator may then select a particular program after a program has been completed by moving switch arm 150a from one contact position to another. Switch 160 has an additional contact 160c adapted to be closed by a movable arm 160a and this contact leads to the switch armature 155a. Switch 160 has a second movable arm 160b

which is adapted to close a contact 160d when arm 160a closes contact 160c. The circuit is then set up to allow an operator to set up the next program unit for automatic connection in the circuit. The movable arm 160d is connected to a line 161 which may be connected to a part of the circuit indicating completion of a program. For example, it may be connected to the reference point R of switch contact 28d which is energized when the stepping switches have returned to home position. Alternatively line 161 may be connected to receive a pulse from the line 61 which signals the completion of a particular program and insures the return of the stepping switches to the home position.

After preselector switch 160 closes contacts 160c and 160d, contact 160c sets up the signal circuit line 51 through a particular program unit by connection with the movable armature 155a and the particular contact with which it is engaged. The coils 155 and 156 are deenergized at this time and the armature 155a stays in position because of its "latched-in" characteristic. After one particular program unit, as for example program unit No. 1, is started, the operator can immediately select the next program for use as, for example program unit No. 2, by moving switch 150 against contact 154 which sets up the energizing circuit for coil 156. When the signal, as aforementioned, indicating completion of program unit No. 1 is passed along line 161, the momentary pulse to coil 156 will disconnect armature 155a from contact 157 for program unit No. 1 and connect it to contact 158 for program unit No. 2 and thus set up the signal circuit line through switch 25 and program unit No. 2.

If the same program is to be repeated, switch 150 is left in the same position, in which case switch armature 155a stays in the same position.

In lieu of the arrangement of the coils 155 and 156, the movable switch arm 150b, for program preselection, may have a bank of contacts leading through corresponding contacts in a rotary stepping switch and to particular programs. Actuation of the signal line 161 is then arranged to energize the operating coil for the stepping switch to step to a contact in circuit with the contact selected by switch 150, at which point the circuit to the operating coil of the stepping switch is interrupted. The particular program thus preselected is then set up for operation with the remainder of the circuit.

It should be understood that while the invention has been disclosed for use with distribution of copies in bins, this should be taken as generally representative of distribution of articles which are moved in single file along a path. Articles other than copy paper may be distributed by means of apparatus and control circuitry as described herein.

We claim:

1. Program control means for automatically depositing preselected numbers of articles in spaced article receiving bins as articles are successively fed in single file relation along a path, including means defining a plurality of successive article receiving and storage spaces spaced along a path, gate means for opening and closing entrance areas for each of said spaces to allow articles to be deposited in selected spaces, article counting means for each of said spaces, selective circuit means for selectively operating said gate means in successive order, signal circuit means energized by said

counting means in response to deposit of a preselected number of articles in a space for disabling the circuit operating means for that space and for simultaneously energizing the circuit means for the next succeeding space, and reset means operated in response to energization of said signal circuit means for resetting said counting means to a base figure.

2. Program control means as set forth in claim 1 characterized by and including reset means for said selective circuit means and automatically operative after operation of the gate means for the last space in successive order to reset said circuit means for the first storage space.

3. Program control means as set forth in claim 1 characterized by and including automatic means responsive to a zero count setting for bypassing said article counting means and for energizing said signal circuit means.

4. Program control means as set forth in claim 1 characterized by and including a plurality of programs each of which is adapted to be associated with said article counting means at a single time, each program including preset means for completing signal circuit means for particular numbers of articles for particular spaces.

5. Program control means for automatically depositing preselected numbers of articles in spaced article receiving bins as articles are successively fed in single file relation along a path, including means defining a plurality of article receiving and storage spaces spaced along a path, gate means for opening and closing entrance areas for each of said spaces to allow articles to be deposited in selected spaces, circuit means for each of said gate means adapted when energized to open a selected gate means, stepping switch means having plural successive contacts each of which is connected to a circuit for one of said gate means, counting means including a multicontact stepping switch adapted to advance one contact in response to deposit of each article in a space, said stepping switch means including a plurality of additional contacts adapted to be successively closed in synchronism with closing of said first named contacts, and a program selector unit having circuits connected to said additional contacts and to the contacts of said copy counting switch, said program selector unit including preset means for closing a circuit through said copy counting switch and through said additional contacts corresponding to a time when a preselected number of copies have been deposited in a preselected space, and means operated in response to completion of said circuit for energizing actuating means for said stepping switch means to disable the circuit means for an open article receiving space while energizing the circuit for the next successive article receiving space.

6. The system as set forth in claim 5 wherein said program selector unit includes means for bypassing the circuit through said copy counting switch and for directly energizing said actuating means in response to a zero article setting for a particular space in said program selector unit to thereby increase speed of changing from one bin to another selected bin.

7. The system of claim 5 characterized by and including a plurality of program selector units connected to said copy counting switch in identical fashion, each

program selector unit being connected to the additional contacts in said stepping switch means, and means for selectively connecting one of said program selector units and the contacts associated therewith with the contacts of said copy counting switch at a single time.

8. The system of claim 5 characterized by and including automatic circuit means for energizing said actuating means to return said stepping switch means to its initial position after said switch has energized the gate operating circuits for all spaces.

9. The system of claim 5 characterized by and including automatic circuit means for returning said copy counting switch to its initial position in response to closure of said circuit through said program selector unit.

10. The structure of claim 5, characterized by and including an operating coil for said stepping switch means, and means responsive to closing of said circuit for operating said coil.

11. Program control means as set forth in claim 5, characterized by and including an operating coil for said multicontact stepping switch, and circuit means for operating said coil to return said switch to an initial position in response to closing of said circuit.

12. Program control means as set forth in claim 5, characterized by and including operating coils for said stepping switch means and said multicontact stepping switch, and means for operating said coils to return said stepping switch means and said multicontact switch to an initial position.

13. A program control means as set forth in claim 12, wherein said means for operating said coils includes automatic means responsive to completion of the article deposit in the last space in programmed sequence for causing operation of said means.

14. Program control means as set forth in claim 5, characterized by and including manual means for disabling said stepping switch means and said multicontact switch and for opening each gate means individually.

15. Program control means for automatically depositing preselected numbers of articles in spaced article receiving bins as articles are successively fed in single file relation along a path, including means defining a plurality of successive article receiving and storage spaces spaced along a path, gate means for opening and closing entrance areas for each of said spaces to allow articles to be deposited in selected spaces, selective circuit means for selectively operating said gate means in successive order, and a plurality of program units for establishing particular numbers of articles in particular spaces, each program unit including means for establishing a signal circuit in response to deposit of a preselected number of articles in a preselected space, means operated by said signal circuit for closing an open gate means while opening the gate means for the next successive space, means for connecting one of said programs in circuit at a time, and means for returning said selective circuit means to its original condition after all of the articles have been deposited in all of the spaces as established by the program unit connected in circuit.

16. Program control means as set forth in claim 15, characterized by and including a stepping switch and an operating circuit therefor for advancing the switch

one step in response to each article deposited in a space, and means operated by said signal circuit for returning said switch to an initial position.

17. Program control means as set forth in claim 16, wherein said operated means actuates means for opening said signal circuit.

18. Program control means as set forth in claim 15, wherein said selective circuit means includes a stepping switch having successive contacts connected to operate each gate in successive order, and means for operating said stepping switch through one step in response to establishment of said signal circuit.

19. Program control means as set forth in claim 18, characterized by and including means operative independently of said signal circuit for actuating said stepping switch to return it to an initial position.

20. Program control means as set forth in claim 19, characterized by and including holding circuit means for returning said stepping switch to its original position.

21. Program control means as set forth in claim 20, characterized by and including automatic means responsive to deposit of a preselected number of articles in the last space in sequence for energizing said holding circuit means.

22. Program control means as set forth in claim 21, characterized by and including manual means for energizing said holding circuit means.

23. Program control means for automatically depositing preselected numbers of articles in spaced article receiving bins as articles are successively fed in single file relation along a path, including means defining a plurality of successive article receiving and storage spaces spaced along a path, gate means for opening and closing entrance areas for each of said spaces to allow articles to be deposited in selected spaces, and a plurality of program units for establishing preselected numbers of articles for deposit in particular spaces, each program unit including means for establishing a signal circuit in response to deposit of a preselected number of articles in a preselected space, means connectable with said program units and operated in response to said signal circuit for opening and closing the gates of selected spaces in an order established by a program unit, means for connecting one particular program unit with said operated means, selection means for selecting a different program unit for later connection with said operated means while said particular program unit is connected, and means operative automatically through said selection means to disconnect said particular program unit from said operated means and to connect said different program unit to said operated means after completion of said particular program unit.

24. Program control means as set forth in claim 23, characterized by and including means responsive to completion of said particular program for causing a signal to pass through said selection means to actuate said operative means.

25. Program control means as set forth in claim 23, wherein said program unit connecting means includes a set of latching relay contacts for each program unit and said operative means includes an operating coil associated with each set of contacts, each operating coil being formed and adapted to close the contacts as-

3,690,643

15

sociated therewith and to open the contacts associated with other coils in response to momentary energization thereof.

26. Program control means as set forth in claim 25, characterized by and including manual switch means 5 for disabling said selection means and operative means while enabling selective manual connection of a selected program unit to said operated means.
